UNITED STATES PATENT OFFICE

106,212

DESIGN FOR A COMBINED LAMP BASE AND CLOCK CASE

Elizabeth Onitch, New York, N. Y.

Application August 11, 1937, Serial No. 71,002

Term of patent 3½ years

To all whom it may concern:

Be it known that I, Elizabeth Onitch, a citizen of Austria and resident of New York City, in the county of New York and State of New York, have invented a new, original, and ornamental Design for a Combined Lamp Base and Clock Case, of which the following is a specification, reference being had to the accompanying drawing, forming a part thereof:

Fig. 1 is a front perspective view of a combined lamp base and clock case, showing my new design.

Fig. 2 is a rear perspective view of the same.

I claim:

The ornamental design for a combined lamp base and clock case, as shown.

ELIZABETH ONITCH.
